UNITED STATES PATENT OFFICE

GEORGES ROUILLER AND JEAN MARION, OF PARIS, FRANCE

PROJECTING MECHANISM

Application filed July 2, 1928, Serial No. 289,914, and in France July 25, 1927.

Our invention relates to a mechanism of simple construction more particularly designed for use in projecting apparatus employed for advertising purposes of the kind which comprise an endless film magazine such as the one described in the U. S. Patent No. 1,713,921, dated May 21, 1929. The presence of delivery drums at the exit and at the inlet of the endless magazine in the device described in said application makes unnecessary those provided on the ordinary projecting apparatus as it is sufficient to produce a flexible loop on both sides of the intermittent delivery device.

On the other hand as the projecting apparatus used for advertising purposes works without supervision the picture framing device may be dispensed with, the places where the ends are assembled being carefully gummed together the same picture will pass exactly at the same place. It will therefore be sufficient to provide an optimum proportion between the window and the intermittent delivery device, and also to very slightly reduce the height of the window to provide for the different pitch of the various bands which are gummed together.

The projecting mechanism according to our invention fulfils all the required conditions and allows of constructing projecting apparatus at a cost much lower than that of existing apparatus besides providing considerable improvements such for example as an accelerated moving away of the picture the continuous regular speed of the obturating device remaining unchanged. This latter device may constitute at the same time a fan and rotate at a speed which is for example three times greater. The appended drawings show by way of example a mode of execution of an apparatus constructed according to the present invention.

Fig. 1 is a part sectional view of our improved mechanism, seen partly from the outside.

Fig. 2 is a sectional view on line 2—2 Fig. 1.

Fig. 3 is another sectional view on line 3—3 Fig. 2.

As will be seen in Fig. 2 the delivery de-

vice 1 designed to intermittently feed the film is secured at one end of the shaft 2 the other end of which is in the shape of a Maltese cross 3 as indicated in Fig. 3.

The shaft 2 rotates in a boss 4 made in one with the casing 8 and is kept in position by means of a washer 6 and a nut 7; the casing 8 is maintained in its correct position by a spur 9. Upon the wall of the casing 8, on the same side as the Maltese cross is mounted a plate provided with fingers 10 rotating on a shaft 11 provided with a bearing, the portion of said shaft which passes through the wall of the casing 8 being slightly eccentric in order to adjust the distance between the plate 10 and the Maltese cross 3; when thus adjusted the shaft 11 is locked by means of a locking nut 12.

The plate 10 is provided with a finger 13 which engaging tangentially one of the grooves of the Maltese cross 3 communicates intermittently to the latter a smooth and noiseless movement of $\frac{1}{4}$ of revolution for every revolution of the plate. On said plate 10 is also provided on the side opposite to finger 13 a second finger 14 diametrically opposite to the first which engages in a groove 15 of plate 16 in order to operate said plate 10 and cause it to move with an uniformly accelerated and then slowed down speed, the shaft 17 which carries the plate 16 being eccentrically to shaft 11. It will be noted that in that case it is the grooved plate that drives the finger 14 or if considering a case of general mechanics it is the slide that drives the crank pin, contrarily to what generally obtains in view of reducing the space required, the arrangement shown being circumscribed in a more reduced space.

On the other part both fingers 13, 14 are placed upon the same plate and as they are of the same diameter the construction is greatly facilitated.

The advance of the film takes place in the passage at the moment when the speed of plate 10 is accelerated, the plate 10 moving at an angle of 90° during the time that the plate 16 moves at an angle of 60° or less according to the given eccentricity.

The cover 18 of the casing 8 constitutes a

bearing for the shaft 17 of plate 16 said shaft carrying a pinion 19 actuated by a pinion 20 made in one with the shaft 21 which is carried by bearings 22, 23 provided in the 5 bosses of frame 5. The shaft 21 may extend outside and is split to receive eventually a handle provided with a pin 24 which allows of operating the mechanism by hand.

A grooved pulley 25 keyed upon shaft 21 10 drives the mechanism by means of a belt driven itself by a motor.

The pinion 26 which is also keyed upon shaft 21 drives a pinion 27 made integral with shaft 28 carrying the obturating device 15 29 which constitutes a fan as already said.

The obturating blade has for example 180° but rotates at a speed which is three times higher than that of the shaft 17 of plate 16 the latter moving a distance of 60° during 20 the same time and simultaneously, the ventilation being consequently much more intensive. The fan suction opening is provided at 30 in the casing 31 secured to the frame 5.

The pinion 19 may eventually drive a pinion 32 keyed upon a shaft 33 carried in bearings 34, 35, said shaft carrying a regulating fly wheel 36 and an endless screw 37 which drive by means of a hollow wheel the vertical shaft of the endless film magazine.

30 A gate 39 carrying spring shoes 40 closes the film passage 38.

It will be understood that the design and detail construction may be variously changed or modified but all such changes are to be 35 considered as within the scope of the following claims.

What I claim and desire to secure by Letters Patent of the United States is:

1. A projecting apparatus mechanism 40 which comprises: a driving shaft, a pinion upon said shaft, a second pinion keyed upon a transverse shaft and in gear with the first, a driving plate carried upon said transverse shaft, a radial groove in said plate, a finger 45 engaging said groove, a second plate carrying said finger upon one side a shaft carrying said plate, a second finger on the other side of the plate, a Maltese cross device operated by said finger, a casing containing both 50 plates, means allowing the driving shafts of both plates to be operated in such a manner that the driving plate of the Maltese cross is driven in a regularly accelerated manner and then delayed.

55 2. A projecting apparatus mechanism which comprises: a driving shaft; a pinion keyed upon said shaft, a second pinion keyed upon a transverse shaft gearing with the first, a driving plate carried upon the transverse shaft, a Maltese cross, a driving plate for same, a casing containing both plates and the Maltese cross, a cover on said casing constituting a bearing for the transverse shaft, a stationary shaft upon which the driving 60 plate of the Maltese cross rotates carried on

the other side of the casing, said shaft being eccentric relatively to the transverse shaft which carries a driving shaft, a radial groove in the driving plate, a finger fixed upon one side of the Maltese cross 70 operating plate engaged with the groove in the driving plate, a second finger upon the Maltese cross operating plate placed diametrically opposite the finger engaged with the groove in the driving plate and on 75 the other side of the plate, a Maltese cross device actuated by the second finger, a shaft upon which the Maltese cross is keyed, a film delivery device keyed upon the end of said shaft, a pinion secured upon the end of the 80 driving shaft, a second pinion in gear with the first keyed upon the upper shaft, and means to drive the vertical shaft of the endless film magazine.

3. A projecting apparatus mechanism comprising: a driving shaft, a pinion keyed upon same; a second pinion keyed upon a transverse shaft in gear with the first, a driving plate carried upon the transverse shaft, an operating shaft for the Maltese cross, a casing containing both plates and the Maltese cross, a slightly eccentric shaft fixed on the casing wall upon which rotates the Maltese cross operating plate, the position of said shaft being adjustable in order to determine 90 the interval between the operating plate and the Maltese cross, a screwthreaded shaft carried upon the stationary shaft, a locking nut upon said screw in order to adjust the position of the shaft, the driving shaft and the 95 Maltese cross operating shaft being eccentrically to each other in such a manner as to drive the Maltese cross operating plate first at a speed which is regularly accelerated and afterwards slowed down, the 100 forward movement of the film taking place during the slowed down period, a radial groove in the driving plate, a finger secured on one side of the operating plate and engaged with the groove in the driving plate, a second finger on the Maltese cross operating plate diametrically opposite on the other side of the driving plate, a Maltese cross actuated by the second finger, a shaft carrying 105 the Maltese cross and a film delivery device, an obturating fan device actuated by the driving shaft and means driven by the pinion on the driving shaft for driving an 110 endless film mechanism.

4. A projecting apparatus mechanism comprising: a driving shaft, a pinion keyed on same, a second pinion keyed upon a transverse shaft in gear with the first pinion, a driving plate upon said transverse shaft, a Maltese cross operating plate, a casing containing both plates and the Maltese cross, a slightly eccentric adjustable shaft on which the Maltese cross operating plate rotates, a groove in the driving plate, a finger fixed upon one side of the Maltese cross operating 115 120 125

plate engaged with the groove in the Maltese cross operating plate, a Maltese cross operated by the second finger, a shaft carrying the Maltese cross and a film delivery device, an obturating fan device operated by the driving shaft, a pinion carried upon a shaft arranged in parallel with the shaft of the driving plate and engaging the plate driving pinion, and an endless screw keyed upon the shaft of the first pinion in order to drive the vertical shaft of the endless film magazine.

10 In testimony that we claim the foregoing as our invention, we have signed our names.

15 GEORGES ROUILLER.
JEAN MARION.
